(57) **CLAIM**

The ornamental design for a bottle, as shown and described.

DESCRIPTION

FIG. 1 is a perspective view of a bottle showing the claimed design;

FIG. 2 is a plan view of the top of the bottle;

FIG. 3 is a plan view of the bottom of the bottle;

FIG. 4 is an elevational view of the first side of the bottle;

FIG. 5 is an elevational view of the second side of the bottle; and,

FIG. 6 is an elevational view of the front side of the bottle. The dash-dot broken lines shown illustrate portions of the bottle. The dash-dot broken lines represent the bounds of the claim. The broken lines form no part of the claimed design.

1 Claim, 7 Drawing Sheets
